[57] CLAIM

The ornamental design for a honey comb shaped golf club divider for a golf bag, as shown and described.

DESCRIPTION

FIG. 1 is a top perspective view of a honey comb shaped golf club divider for a golf bag showing my new design in use; FIG. 2 is a top plan view thereof; FIG. 3 is a side elevational view thereof; FIG. 4 is a front elevational view thereof; and, FIG. 5 is a rear elevational view thereof. The broken lines showing of a portion of a golf bag in FIGS. 1, 3, 4 and 5 are for illustration purpose only and forms no part of the claimed design.
